Attorney

UNITED STATES PATENT OFFICE.

EDWARD OSWALD, OF SYRACUSE, NEW YORK.

WATER WHEEL.

Application filed June 8, 1921. Serial No. 475,975.

To all whom it may concern:

Be it known that I, EDWARD OSWALD, a citizen of the United States, residing at Syracuse, in the county of Onondaga and State of New York, have invented certain new and useful Improvements in Water Wheels, of which the following is a specification.

This invention relates to improvements in water wheels of the "current motor type", and has for its object to provide a novel, simple and powerful device of the class which consists of a disk-shaped wheel arranged to operate in a vertical plane, and which may be wholly or partially submerged in a river or other running stream by the current of which it is operated. A further object is to provide a plurality of equidistantly spaced hinged-blades, which are disposed in corresponding annular rows around the opposite faces of the wheel adjacent the periphery thereof, the said blades being pivoted in such manner that a portion of them present relatively broad-blade surfaces extending at right angles across the course of the flowing stream, while the remaining blades, particularly those at the top end and at the opposite or down-stream edge of the wheel, are closely folded against the faces of the wheel, so as to offer the least possible resistance to the rotation of the wheel. A further object is to provide means for gearing the wheel to a power transmission shaft. And a further object is to provide means for automatically and successively extending and folding the blades.

The various features and parts of the invention will be understood from the detailed description which follows and by reference to the accompanying drawings, in which—

Figure 1 is a side elevation of the complete wheel; showing the manner of folding and extending the blades. Fig. 2 is a top-plan view of the same, with the gears omitted. Fig. 3 is a front end elevation of the wheel. Figs. 4 and 5 are respectively a broken section and a broken elevation of a modified structure. And Figs. 6 and 7 are respectively a face and an end view of one of the blades.

In the drawing, 2 represents the frame

which supports the power generating mechanism, and comprises an open rectangular base 2', from the side rails of which rise angular brackets 2^a, each of which is provided with shaft bearings 2^b, in which the main wheel-shaft 3' is journaled. 3 represents the current driven wheel, which is preferably a plain disk of any suitable material, which is mounted concentrically and rigidly on the shaft 3', and is rotatable in the clear space between the brackets 2^a. In practice my power apparatus may be partially submerged in the running water of a river or other stream, as indicated by the dotted line *x* in Fig. 1, or the device may be entirely submerged in the stream (not shown). The wheel 3 is operated by the current, which in the present case flows from left to right, as indicated by the horizontal arrow in Fig. 1, and for this purpose the opposite sides of the wheel are provided with a number of pivoted or hinged blades 4—4', preferably made of sheet metal, and arranged in pairs, as shown in Figs. 2 and 3. In order to provide in a simple manner for pivoting the blades, the opposite faces of the wheel 3 are provided at regularly spaced intervals with a plurality of perforated lugs 3^a, preferably arranged in pairs, which align radially, and the blades are provided with pintles or rods 4^a, which are journaled in the said lugs, as best seen in Fig. 1. The pintles 4^a are applied to the substantially straight edges 4^b of the blades, and this leaves the opposite edges 4^c free, and the edges 4^c are preferably slightly rolled or curved outwardly away from the faces of the wheel 3, as best shown at the right, in Fig. 2. The opposite ends of the blades are bent at right angles and support the pintles, and the portions adjacent the pintles are formed into angular shoulders 4^d, which when the blades are extended, as shown at the left in Figs. 1 and 2, bear against the opposite faces of the wheel and tend to hold the blades extended substantially at right angles to the plane of the wheel, and therefor in the position to receive the full force of the current. When in operation, the wheel 3 rotates in the direction indicated by the oblique arrow in

Fig. 1, and as each pair of blades 4-4' reaches the top and passes the line of the vertical axis of the wheel, the blades gravitate or swing downwardly towards the left and become fully extended. Then as the blades successively come in contact with the current, the current drives the lower portion of the wheel towards the right. The force of the current acts upon each pair of blades 10 positively from the time the edges 4^b of the blades are moved below the line of the horizontal axis of the wheel (see line α in Fig. 1), and the current continues to drive the blades until they again cross the line of the vertical axis at the bottom of the wheel. After the latter point is passed the resistance of the blades decreases, and as the lower portion of the wheel moves upwardly, each pair of the blades in sequence gradually swings inwardly towards the wheel, where they remain in the fully folded position until the revolution of the wheel is completed. By disposing the blades 4-4' equidistantly as shown, the driving action 25 of the current and the power generated thereby is continuous and regular. The transmission of the power is effected by the following means: 5 represents a relatively large bevel gear, which is rigid on one end 30 of the shaft 3', and meshes with a bevel pinion 5', which is rigid on an upright shaft 5^a, the latter shaft being journaled in bearings 5^b, and being held in place by a collar 5^c, and a socket bearing 2^c.
35 In Figs. 4 and 5, the modification consists of a relatively thick wheel 6, the periphery 6' of which is V-shaped in cross-section for cutting the water. This wheel is mounted on a shaft 6^a. The opposite 40 sides of the wheel 6 are provided with substantially flat wings or blades 7-7', which are disposed in angular recesses formed in the opposite faces of the wheel, and these may be arranged in annular rows similar 45 to the disposition of the blades in Figs. 1, 2 and 3. The blades 7 are pivoted in the deeper portions of the sockets 7^a by pintles 7^b, and beyond the pintles the blades flare outwardly at an angle, which is slightly 50 obtuse for providing margins or shoulders 7^c, the free ends of the latter project slightly beyond the plane faces of the wheel 6. The full lines in Fig. 4 show the blades folded and disposed in the sockets 7^a, which 55 is the idle position. When the wheel is rotated in the upstream direction the blades 7, like the blades 4, gravitate, or are forced out of the recesses 7^a and become extended substantially at right angles to the opposite 60 faces of the wheel, as shown by dotted lines in Fig. 4, and by the full lines in Fig. 5, and when the blades are so extended, the free ends of the shoulders 7^c meet in sockets or transverse openings 6^b. By this construction and arrangement, the blades may

only be extended to the extent indicated in Fig. 4, and at such times the shoulders 7^c tend to hold the blades of each pair in a common plane. The folding of the blades 7 is accomplished in the same manner, as shown and described for the preferred structure, as by the pressure of the water against the shoulders 7^c, which takes effect shortly after the blades pass the line of the vertical axis at the bottom of the wheel, as described.

My improved water wheel is extremely simple in construction, arrangement and operation and can be produced and maintained at slight expense. The relatively broad spread of the wings or blades 4 and 7, which are successively moved into the path of the current, and the arrangement whereby several of the blades are being acted upon by the current at the same moment, while the other blades are in the folded positions in which they offer the least resistance to the rotation of the wheel, enables me to generate a relatively high power with scarcely any loss, when the product and output of the wheel is considered in connection with the volume of the water and the rate of the flow of the current.

The entire absence of springs, cams and similar attachments for aiding or controlling the blades while performing their functions, tends to increase the output in power units and renders my motor more simple, positive and reliable in its working, than any other device of the class known to me.

Having thus described my invention, what I claim as new, is—

1. A water wheel comprising a horizontal shaft, a disk rigid on said shaft and rotatable in a vertical plane, annular rows of gravitational blades having their inner and outer circumferential edges bent at right angles, pintles carried by the disk and passing through the bent-over edges to pivotally mount the blades on the opposite plane surfaces of the disk, said blades being arranged in pairs and adapted to be automatically extended at right angles to said surfaces during one-half of each revolution of the disk, said blades also adapted to become folded closely against said surface during the other half revolution of the disk, and means formed on the bent-over edges for limiting the movements of said blades on their pivots.

2. A water wheel comprising a rotatable disk formed on its opposite faces with angular recesses, and a blade pivoted in each recess for lying therein and having a shoulder extension beyond its pivot to project from the adjacent side face of the disk when the blade is folded into its recess.

3. A water wheel comprising a rotatable disk formed on its opposite faces with recesses, said recesses communicating through

the disk with corresponding recesses on the opposite side or face thereof and thereby connecting the recesses in pairs, one recess of each pair being arranged on the opposite face of the disk from the companion recess, and a blade pivoted in each recess and having a portion adapted to abut and

brace against the corresponding portion of the oppositely disposed blade through the communicating opening when the blades are 10 in operative position.

In testimony whereof I affix my signature.

EDWARD OSWALD.
